TAB STRIP FIN FOR HEAT EXCHANGER
CORES

Ray L. Lyerly and Sven Holm, Wellsville, N. Y.,
assignors to The Air Preheater Corporation,
New York, N. Y.

Application June 4, 1951, Serial No. 229,805

6 Claims. (Cl. 257—245)

1

The present invention relates to apparatus for the exchange of heat between two confined fluids and particularly to an improved form of extended fin surface for heat exchangers of the plate type.

A familiar type of heat exchanger for two confined fluids comprises metallic plates spaced apart to form fluid passages through which one fluid is circulated for transferring heat through the passage wall formed by the metallic plate to another fluid in an adjacent passage, the passages for the heating fluid and fluid to be heated being arranged in alternation. The spaces between the adjacent plates are closed along one pair of opposite edges to close the side of the fluid passages.

To increase the efficiency of heat transfer between the two fluids through the passage walls the latter are frequently provided with extended surface in the form of fins that project into the fluid streams. The present invention contemplates improvements in extended surface in the nature of preformed elements that are mounted between and bonded to parallel plates to constitute extended surface of the passage walls formed by the plates. Specifically the invention is directed to an improved form of so-called interrupted strip fin that lies in the fluid passage and extends in the direction of fluid flow.

In designing heat exchangers generally and particularly heat exchangers for gas turbine application, it is desirable to arrange the unit for counterflow. Especially if higher effectivenesses are required, say 80% and higher, the counterflow principle is the only practical flow arrangement. The only disadvantage is that the designer does not have the freedom to select the optimum ratio of frontal areas for the two fluids as this ratio is established in counterflow and the frontal area is common for both fluids.

In a gas turbine application, the heat is exchanged between gas at approximately atmospheric pressure and air at a pressure 4 or 5 times atmospheric pressure. The extended heating surface on gas side should be some very efficient surface as pin-fins extending between widely spaced plates forming passages. The extended heating surface on the air side has heretofore been a channel shaped element or plates with corrugations, generally square, forming continuous strip fins extending between closely spaced plates that form the air passages.

It is the object of this invention to provide an extended surface element to replace the continuous fin surface heretofore used on the air side. The surface contemplated will have a higher heat transfer rate and this improvement in heat

2

transfer is even more pronounced at low or part loads since the film coefficient decreases with the .8 power with the mass velocity for continuous passages and approximately with the .65 power for interrupted passages.

The invention will best be understood upon reference to the following description of illustrative embodiments thereof when read in conjunction with the accompanying drawings in which:

10 Figure 1 is a transverse sectional view through part of a heat exchanger having passage walls provided with extended surface in accordance with the present invention.

15 Figure 2 is a fragmentary perspective view on an enlarged scale of one of the fin elements illustrated in Fig. 1.

20 Figure 3 is a plan view of a metallic blank or strip from which the fin element of Fig. 2 is formed.

25 Figure 4 is a sectional view longitudinally of the heat exchange passages on the line 4—4 in Figure 1.

30 Figures 5 and 6 are sectional views similar to Figure 1 illustrating modified forms of the fin element.

35 In Figure 1 the numerals 10 and 11 designate a pair of metallic plates spaced apart to form a passage 12 through which air or other fluid to be heated is circulated in heat transfer relationship with another fluid such as hot gas flowing through passages 13 that alternate with the air passages 12 and which are separated therefrom by passage walls constituted by the plates 10 and 11. The extended fin surface projecting from the walls 10 and 11 into the air passage 12 is, in accordance with the present invention, made up of a plurality of fin elements, designated as a whole by the numeral 14, disposed in side by side relation in the passage 12 and preferably bonded to the confronting surfaces of the plate walls 10 and 11 that bound the passage.

40 Each of the fin elements 14 is formed from an elongated strip of metal 15 which is slit at 16 as indicated in Fig. 3 part-way in from each longitudinal side edge 17 so that tabs may be bent upwardly and downwardly, as shown in Figure 2, from the web or body portion 18 of the strip. The tabs 20 are bent upwardly along opposite longitudinal edges of the body or web 18 of the strip in alternation with other tabs 21 which are bent downwardly from the body portion. The extreme marginal edges of all the tabs are also bent to parallelism with the web 18 so as to provide lateral flanges 22 at right angles to the tabs 20. These flanges 22 consti-

tute foot-like portions which rest against the surfaces of the plates 10 and 11.

In constructing a heat exchange envelope a plurality of the fin elements 14 shown in Fig. 2 are assembled in side by side relation between the two plates 10 and 11 which constitute the walls of a heat exchange envelope. The elements 14 are mounted on the plate 11 so that the side faces 23 of the lateral flanges 22 on adjacent elements 14 are in contact with each other as appears in Fig. 1. The plate 11 is then laid on the juxtaposed elements 14 and the elements at the extreme side edges of the plates 10 and 11 may be tack welded thereto prior to brazing all of the fin elements to the plates 10, 11, strips of brazing metal etc. having been laid between the element feet 22 and the plates 10, 11 in the course of assembly.

The relative proportions of the web 18 of the fin element 14 and the tabs 20, 21 are such that the hydraulic diameter of either of the spaces *a*, Fig. 1, between two tabs 20 or 21 on a particular element equals the hydraulic diameter of the space *b* formed between two adjacent elements 14 by the spacing apart of the latter through the foot-like lateral flanges 22 of these elements.

On the gas side of the plate walls 10, 11 extended surface may be provided in the passages 13 by pin-fins 30 as more fully disclosed in the co-pending application of Sven Holm and Arthur Jensen, Serial No. 752,008, filed June 3, 1947, now Patent #2,595,457 granted May 6, 1952. In a heat exchanger made up of a plurality of "envelopes" of the type described, the side edges of the passages are closed by plate members 31 and, when the gases flow in passages 13 in counter-flow relation to the air in passages 12, the corresponding spaces between adjacent envelopes are closed along the side edges of the latter by other bridging elements or strips 32 in conventional fashion.

In Fig. 5 the web portion 33 of each fin element is formed with alternately raised and depressed portions 35 and 36 so that the surface of the web is interrupted and non-planar in the direction of gas flow so as to avoid formation of a laminar boundary layer along the longitudinal surface of the web 33.

The fin element 34 shown in Fig. 6 is similar to that of Fig. 1 except that the tabs are bent more to a V-shape than to the U or channel shape shown in Fig. 1.

The fin elements 14 as described permit a more balanced heat exchange design when used with other highly efficient surfaces on the other side of dividing wall, resulting in a short flow path in the heat exchanger. The elements 14 are self-spacing and the envelope may be filled with the elements and the outside ones can be tack welded to plates before brazing. There is a minimum of doubling up of material. A conventional surface built up of channel components or corrugated sheets has 50% of doubled up surface, i. e. half the wall surface or section is contacted and overlaid by a corresponding part of a fin so that there is a double thickness of metal in these regions amounting in all to about half the wall surface. The surface here described has only between 16 and 17% doubled up surface.

A further advantage is that an interrupted strip fin may be produced without the usual large loss of material in cutting away parts of continuous longitudinal fins to create the interrupted form. Here the only loss of material is the very slight amount entailed in making the slits 16.

What we claim is:

1. In a heat exchanger having metallic plates spaced apart as walls of fluid passage; a plurality of longitudinal fin elements mounted in said passage in side by side relation each comprising an elongated metallic strip disposed in spaced relation to said walls and formed with pairs of marginal tabs extending from each longitudinal edge alternately in opposite directions from the plane of the body of the strip toward the opposite walls of said passage to provide alternately upright and inverted generally U-shaped channel parts with end portions of the tabs contacting said walls.
2. In a heat exchanger having metallic plates spaced apart as walls of a fluid passage; a plurality of longitudinal fin elements mounted in said passage in side by side relation each comprising an elongated metallic strip disposed in spaced relation to said walls and formed with pairs of marginal tabs extending from each longitudinal edge alternately in opposite directions from the plane of the body of the strip toward the opposite walls of said passage to provide alternately upright and inverted generally U-shaped channel parts; and lateral flanges at the extreme end portions of the tabs bent laterally at approximately a right angle to each tab to provide foot-like portions in contact with the walls of said fluid passage, the side faces of the flanges contacting corresponding parts of the next contiguous fin elements at either side thereof to subdivide the space between said plates into passage sections located between contiguous elements and adjacent to other passage sections enclosed within said U-shaped channel parts of each element.
3. In a heat exchanger having metallic plates spaced apart as walls of a fluid passage; a plurality of longitudinal fin elements mounted in said passage in side by side relation each comprising an elongated metallic strip located centrally between said walls formed with pairs of marginal tabs extending from each longitudinal edge alternately in opposite directions from the plane of the body of the strip toward the opposite walls of said passage to provide alternately upright and inverted generally U-shaped channel parts with end portions of the tabs contacting said walls, the width of the body portion of said element dividing the height of the fluid passage to form two complementary portions of the same frontal area and hydraulic diameter bounded laterally by the tabs extending normally from the body portion of the tabs.
4. In a heat exchanger having metallic plates spaced apart as walls of a fluid passage; a plurality of longitudinal fin elements mounted in said passage in side by side relation each comprising an elongated metallic strip located centrally between said walls; pairs of marginal tabs extending in opposed relation in one direction from the plane of the body of each strip to provide generally U-shaped upright channel parts; other pairs of opposed tabs extending in the opposite direction from the body of the strip to provide inverted generally U-shaped channel parts; lateral flanges at the extreme end portions of the tabs bent laterally at approximately right angles thereto to provide foot-like portions in contact with the walls of said fluid passage and the side faces of said flanges contacting corresponding parts of the next contiguous fin elements at either side thereof to subdivide the space between said plates into passage sections located between contiguous elements and adj-

cent to other passage sections enclosed within said U-shaped channel parts of each element, the width of the body portion of said element bisecting the height of the fluid passage to form two complementary portions of the same frontal area and hydraulic diameter bounded laterally by the tabs extending normally from the body portions of the strip and the width of the lateral flanges of contiguous members being such that when their flanges abut the passage areas between the tab elements of contiguous fin elements have a frontal area and hydraulic diameter the same as embraced within a U-section of a fin element.

5. In a heat exchanger having metallic plates spaced apart as walls of a fluid passage; a plurality of longitudinal fin elements mounted in said passage in side by side relation each comprising an elongated metallic strip located centrally between said walls formed with pairs of marginal tabs extending from each longitudinal edge alternately in opposite directions from the plane of the body of the strip to provide alternately upright and inverted generally U-shaped channel parts, the width of the body portion of said element subdividing the height of the fluid passage to form two complementary portions of the same frontal area and hydraulic diameter bounded laterally by the tabs extending normally from the body portion of the tabs and the 30

spacing of the U-sections of any two contiguous fin elements being such as to form therebetween another passage section of a frontal area corresponding to that embraced with a U-section of a fin element.

6. In a heat exchanger having a pair of metallic plates spaced apart as walls of a fluid passage; longitudinally extending fin elements constituting extended surface projecting from said walls into said passage comprising; elongated metallic strips having the body portions thereof disposed centrally between said plates and parallel thereto with side portions of the strips extending alternately in opposite directions substantially normally to its body toward both said wall plates of the passage and subdividing the latter.
